OF MAINE.

MILL-PINION.

1,171,532.

Specification of Letters Patent.

Patented Feb. 15, 1916.

Application filed May 4, 1915. Serial No. 25,696.

To all whom it may concern:

Be it known that I, WESLEY G. NICHOLS, a citizen of the United States, and a resident of Chicago Heights, in the county of Cook 5 and State of Illinois, have made and invented certain new and useful Improvements in Mill-Pinions, of which the following is a specification.

This invention relates to mill pinions, and 10 more particularly to one formed of manganese steel, the inherent toughness, strength, and wearing qualities of which metal render it particularly adapted for use in such structures.

15 In forming large castings of manganese steel, amounting, in the present instance, to as high as fifteen to twenty tons, it is practically impossible to form the cope side of the casting absolutely sound, segregated defects and inherent checks being liable to predominate throughout this part of the casting, due primarily to excessive strains from shrinkage, and the inability to properly feed the cope side of the casting.

20 It is therefore the purpose of my invention to provide a cast manganese steel pinion of such design and arrangement that those parts thereof which must withstand enormous strains and stresses, will have been 25 formed in the drag side of the mold, and those parts of the casting which occupy the cope end thereof are merely subjected to compressive strains which they are capable of successfully withstanding.

30 A further object is to provide a manganese steel pinion wherein the shaft is formed of two half-shafts, upon the abutting ends of which is shrunk a toothed shell, so that, should either end of the shaft be- 35 come broken, it may be removed and a new one substituted therefor, so that the entire pinion or shaft need not be discarded.

In addition to the foregoing, and made 40 possible by the manner in which the above- mentioned objects are attained, I provide the half-shafts with outstanding flanges which are adapted to bear against the sides of the toothed shell, so as to prevent the overall length of the pinion changing. The 45 confronting shoulders defined by the flanges also prevent the shifting of the toothed shell along the pinion shaft, this having heretofore been a decided drawback in the formation of mill pinions in two or more pieces, 50 all danger and likelihood of this shifting of

the toothed shell being eliminated in the present construction.

Other objects and advantages will appear as the description proceeds, wherein it is to be understood that changes in the precise 60 embodiment of the invention can be made within the scope of what is claimed, without departing from the spirit of the invention.

The preferred embodiment of my invention is disclosed in the accompanying drawings, wherein:

Figure 1 is a view in end elevation of a mill pinion embodying the characteristic features of my invention, portions of the pinion being broken away and represented 70 in section; Fig. 2 is a view in side elevation of the foregoing, with the lower half thereof broken away to more clearly disclose the novel structural features involved.

Referring specifically to the several views, 75 the mill pinion, considered in its entirety, is formed with the two half-shafts 5, 6, the one being a counterpart of the other, and each including the shoulder portion 7 and wabbler or power transmitting end 8. The 80 half-shafts are cored, so as to define the central openings 9, the same materially lightening the entire structure without interfering with the requisite strength 85 thereof. The wabbler or power transmitting end 8 includes the usual arrangement of spaced fingers or projections 10, which are adapted to interlock with the corresponding projections which are formed upon the end of the power shaft. 90

The two half-shafts are placed end to end, the wabbler ends being outermost, and upon the meeting or adjacent ends of these half-shafts is shrunk the manganese toothed shell 11. In actual practice in rolling mills, 95 there is always danger of the rolls becoming fouled by a cold ingot, and under such conditions there is likelihood of either the wabbler ends or the journal portions of the pinion shaft becoming broken, the wabbler 100 or power transmitting ends 8 being subjected to excessively high strains under these circumstances. By forming the mill pinion with two half-shafts, rather than one integral shaft, allows the two wabbler 105 ends to occupy the lowermost positions, within the molds, that is, within the drag side thereof.

In forming large castings of manganese steel, that portion of the casting which 110

- occupies the drag side of the mold, is many times stronger than the part which occupies the cope side, the inherent defects and checks always predominating in the cope 5 side of the casting. The formation of the mill pinion with two half-shafts prevents the entire shaft from being discarded should it become broken, as a new half-shaft can be substituted for the one which failed.
- 10 The shaft which forms part of the mill pinion is at times exposed to terrific end thrusts, and in order to prevent any likelihood of the overall length of the shaft changing, and at the same time to insure 15 against the shifting of the toothed shell along the shaft, I provide the half-shafts 5 and 6 with the outstanding flanges 12, which are positioned adjacent the meeting ends of the half-shafts and which define the confronting shoulders 13. The toothed shell 11 is in the form of a drum or collar, and is provided at its ends with the annular recesses 14, of such size as to nicely accommodate the flanges 13 therein. A slight 20 clearance is left between the outer peripheries of the flanges and the inner surfaces of the recesses, so as not to interfere with the tight shrinkage fit between the toothed shell and the meeting or adjacent ends of the 25 half-shafts. In order to further lock the toothed shell to the half-shafts, each of the latter is provided with the slotted keyway 15, the inner surface of the toothed shell being provided with a corresponding 30 keyway 16, into which is driven the key 17, thus securely holding the various parts in proper position. The toothed shell is accordingly held against either shifting longitudinally of the pinion shell, or against 35 rotation with respect thereto. The abutment between the flanges of the half-shafts and the toothed shell further prevents any danger of the overall length of the mill pinion changing, due to end thrusts; the two 40 half-shafts and toothed shell forming a mill pinion, which, to all material respects, is integral throughout, and yet possesses very substantial advantages over such construction, as pointed out.
- 45 I do not wish to limit myself to the formation of shafts having a gear wheel thereon, as the construction is equally adaptable for the formation of a mill roll; the toothed shell in this instance referring to the shell, 50 which is provided with a circumferential groove or grooves.
- What I claim is:
1. An article of the class described comprising a divided shaft, flanges carried
- thereby and removed a slight distance from 60 the adjacent extremities of said divided shaft, said flanges defining spaced confronting shoulders, and a drum spanning the division of said shaft and contacting with said confronting shoulders. 65
2. An article of the class described comprising half-shafts with removed power transmitting ends, flanges carried by, and spaced a distance from, the adjacent extremities of said half-shafts, and a shell carried by the adjacent ends of said half-shafts and contacting with the confronting shoulders defined by said flanges. 70
3. A mill pinion comprising cast manganese steel half-shafts with power transmitting ends, flanges carried by, and spaced a distance from, the adjacent extremities of said half-shafts, and a cast manganese steel toothed shell carried by the adjacent ends of said half-shafts and contacting with the confronting shoulders defined by said flanges. 75
4. An article of the class described comprising half-shafts, flanges carried by, and spaced a distance from, the adjacent extremities of said half-shafts, a drum provided with annular recesses at the opposite ends thereof, said drum fitting upon the adjacent extremities of said half-shafts and receiving said flanges within said annular 80 recesses. 85
5. An article of the class described comprising a divided shaft, thereby defining two half-shafts, a toothed shell spanning the division between and rigidly secured to 95 said half-shafts; means engaging said shell and holding the same against shifting lengthwise of said half-shafts, said half-shafts formed with power transmitting ends, and with intermediate journal portions. 100
6. An article of the class described, comprising a hollow divided shaft of manganese steel, the two sections thereof forming hollow half-shafts; a drum spanning the division of said shaft and holding said half-shafts in alinement; means carried by said half-shafts engaging said drum and holding the drum against movement with respect thereto, said half-shafts provided with 105 journal portions. 110

Signed at Chicago Heights, in the county of Cook and State of Illinois, this 28th day of April A. D. 1915.

WESLEY G. NICHOLS.
